IN COUNSEL.
George W. Hoar
Tylor's attorney, Paul N. Gooding.

UNITED STATES PATENT OFFICE.

GEORGE W. HOAR, OF WALTHAM, MASSACHUSETTS.

FASTENER.

1,178,921.

Specification of Letters Patent. Patented Apr. 11, 1916.

Application filed December 27, 1915. Serial No. 68,669.

To all whom it may concern:

Be it known that I, GEORGE W. HOAR, a citizen of the United States, residing at Waltham, in the county of Middlesex and 5 State of Massachusetts, have invented new and useful Improvements in Fasteners, of which the following is a specification.

This invention relates to improvements in fasteners particularly adapted for fastening 10 carriage curtains and the like.

The object of the invention is to provide an inexpensive and simple fastener adapted to secure the edges of curtains or side pieces of vehicles to the body portion thereof, said 15 fastener having means to prevent said curtain from becoming detached from said body accidentally, but permitting said curtains to be easily and quickly detached when desired.

20 The invention consists in the combination and arrangement of parts set forth in the following specification and particularly pointed out in the claims.

Referring to the drawings: Figure 1 is a 25 transverse section through the holder of the fastener embodying my invention and illustrating the resilient member arranged in its proper position with relation to the top of said holder. Fig. 2 is a detail plan view of 30 the back of the holder of said fastener. Fig. 3 is a section taken substantially on the line 3—3 of Fig. 1 illustrating the stud in its locked position in the holder. Fig. 4 is an enlarged detail section taken substantially 35 on the line 4—4 of Fig. 3. Fig. 5 is a section similar to Fig. 3, illustrating the position of the stud with relation to the holder immediately prior to its being withdrawn from said holder. Fig. 6 is a section taken 40 on the line 6—6 of Fig. 5. Fig. 7 is a modified form of resilient member. Fig. 8 is a section taken on the line 8—8 of Fig. 1.

Like numerals refer to like parts throughout the several views of the drawings.

45 In the drawings, 8 is the holder and preferably embodies in its construction a top 9 formed of sheet metal with a peripheral flange 10 formed integral therewith. A back 11 also formed of sheet metal is arranged 50 substantially parallel with the top and preferably secured thereto by tongues 12 preferably formed from material constituting said flange 10. The tongues 12, preferably three in number, are arranged to project 55 through perforations 13 in said back and to

be bent or clenched against the outer surface of said back to rigidly secure said back in contact with the edge of the flange 10. A resilient member 14, preferably constructed of wire, is arranged in circular 60 form 17 within said casing between the top and back members thereof and along the inside of the flange 10. The end portions 15 and 16 of the resilient member 14 are bent inwardly with respect to the circular 65 portion 17 of said resilient fastener and arranged substantially side by side. These end portions 15 and 16 extend substantially across the central portion of said holder with the extremities 18 and 19 thereof offset 70 so as to normally engage each other and to be retained in such a position by the resiliency of the material thereof.

The top 9 and back 11 are each provided with an aperture 20, the aperture for said 75 top being substantially in alinement with the aperture for the back and both are arranged substantially central with respect to said members so as to expose the intermediate portions of the end portions 15 and 16 80 of the resilient member. The holder 8 is also provided with a depression 21 formed preferably in the back 11 adjacent to one side of the aperture 20 and in alinement with the extremities 18 and 19 of the 85 resilient member 12.

Upon the back of the holder at one side of the aperture 20 is a pair of abutments 22 and 23 preferably formed by depressing the inner face of said back at 21 which abutments are arranged to engage the extremities 18 and 19 respectively when said extremities are moved into said depression to 90 preferably force said extremities together and positively retain the same in their contracted relation. A stud 24, preferably cylindrical in form, is adapted to be inserted in said apertures between the members 15 and 16 of said resilient member. The extremity of said stud is preferably 95 chamfered or rounded at 25 so as to permit said end to be readily inserted between said members. An annular groove 26 is formed adjacent to the rounded extremity 25 of said stud to form a shoulder 27. The stud 100 24 is inserted in said holder until the groove 26 is opposite the members 15 and 16, permitting said members to spring into said groove back to their contracted positions 105 from which they were moved during the in- 110

sertion of the head end of said stud. Under ordinary conditions, the end portions 15 and 16 rest against the inner surface 28 of the top 9 of said holder, but should an attempt be made to remove the holder from the stud or to apply a direct longitudinal pressure to said holder relatively to said stud in the direction of the arrow *a*, Fig. 3, to withdraw said stud from said holder, the shoulder 27 will engage the members 15 and 16 and depress said members so that the extremities 18 and 19 thereof will be forced against the inclined surfaces 22 and 23 into the depression 21, causing said extremities to be forced firmly together and held while said pressure on said stud is maintained, and thereby more firmly gripping said stud and absolutely preventing the removal of said holder from said stud.

To insure a free movement of the members 15 and 16 between the top 9 and back 11, spacers 29 and 29' have been provided preferably formed integral with the back by partially detaching a portion of material thereof and bending said material in the direction of the top 9 so as to engage the face 28 thereof. The holder 8 is usually attached to the side curtains of the motor vehicle represented at 30 while the stud 24 is attached to the body of the vehicle. When used in this connection, the side of said holder opposite the depression 21 and as indicated by the letter *A* is disposed toward the edge of the curtain or side and when it is desired to detach the holder from the stud the side of said holder *A* is tipped with relation to the stud 24 in the direction indicated by the arrow *b*, see Fig. 5. During the tipping of said holder, as stated, the rim 31 of the head of said stud is adapted to engage the members 15 and 16 upon the opposite side of the aperture 20 from the depression 21 and separate said members so as to permit the head of said stud to pass therebetween.

As the rim 31 engages the members 15 and 16, as stated, the rim 32 of said stud upon the opposite side of the annular groove 26 engages the undersides of said members 15 and 16 adjacent to the depression 21 and has a tendency to force said members upwardly away from said depression and against the inner face 28 of the top 9, thus enabling the rim 31 to readily separate the resilient end portions 15 and 16, moving the extremities 18 and 19 thereof into the positions illustrated in Fig. 6. In Fig. 7 I have illustrated a resilient member 33 having end portions 34 and 35 formed straight instead of offset as in Fig. 1. To accommodate this type of resilient member the inclined surfaces 22 and 23 illustrated in Fig. 4 may be placed at a slightly greater distance apart than shown in said Fig. 4, otherwise the construction is the same. The

spacer 29 is disposed between the members 15 and 16 and has an additional function in that it is formed tapering as illustrated in Fig. 8, so as to properly space the members 15 and 16 during the assembling of the device.

Having thus described my invention what I claim and desire by Letters Patent to secure is:

1. A fastener having, in combination, a pair of resilient members yieldingly disposed in contracted relation with respect to each other, a holder for said members having a depression constructed and arranged to receive the free ends of said members, a stud adapted to be inserted in said holder between said resilient members, and a shoulder on said stud adapted to be engaged by said resilient members when pressure is applied to said holder longitudinally of said stud in one direction, to force the free ends of said resilient members into said depression, whereby said members will be held contracted and the removal of said holder from said stud be prevented. 90

2. A fastener having, in combination, a pair of resilient members arranged with their free ends normally substantially in contact with each other, a holder for said members having an aperture extending therethrough, said holder also having a depression arranged in alinement with the free ends of said resilient members, a stud adapted to be inserted into the aperture in said holder between said resilient members, and a shoulder formed upon said stud adapted to be engaged by said resilient members when pressure is applied to said holder longitudinally of said stud in one direction, to force the free ends of said resilient members into said depression, whereby said resilient members will be positively locked together and the removal of said holder from said stud prevented. 100 105

3. A fastener having, in combination, a holder provided with an aperture, said holder also having a depression at one side of said aperture, a resilient member arranged within said holder, encircling said aperture, the end portions of said resilient member being arranged, transversely of said aperture, the extremities of said end portions being arranged to normally aline with said depression, a stud adapted to be inserted in said aperture between the end portions of said resilient member, and a shoulder on said stud adapted to be moved to engage said end portions and move the same into said depression to positively hold said end portions in normal relation, whereby the withdrawal of said stud from said holder will be prevented. 110 115 120 125

4. A fastener having, in combination, a holder provided with a centrally disposed aperture, said holder also having a depres- 130

5 sion on one side of said aperture, a resilient member arranged within said holder, the end portions of said resilient member being arranged, transversely of said aperture, the extremities of said end portions being normally yieldingly held in contracted relation and in alinement with said depression, and a cylindrical stud adapted to be inserted in said aperture between the end portions of 10 said resilient member, said stud having an annular groove formed adjacent to the extremity thereof, adapted to receive said end portions, said annular groove forming a shoulder constructed and arranged to engage said end portions and force the extremities thereof into said depression when attempt is made to withdraw said stud from 15 said holder in a direction longitudinal of said stud, whereby the extremities of said end portions will be positively held contracted and the withdrawal of said stud prevented.

5. A fastener having, in combination, a holder including a top, a back secured to said top, said top and said back having apertures extending therethrough substantially in alinement with each other, a resilient member arranged within said holder intermediate of said top and said back, the 20 end portions of said resilient member being arranged transversely of said apertures and in normally yieldingly contracted relation, said back also having a depression formed therein at one side of said aperture and 25 alining with the extremities of said end portions, a stud adapted to be inserted in said casing between said end portions, and a shoulder formed upon said stud constructed and arranged to engage said end portions 30 and force the extremities thereof into said depression, whereby said stud will be firmly gripped and the withdrawal thereof prevented.

6. A fastener having, in combination, a holder provided with an aperture, a pair of abutments on said holder at one side of said aperture, a pair of resilient members arranged transversely of said holder over said aperture with the free ends of said resilient 45 members substantially alining with said abutments, a stud adapted to be inserted through said aperture between said resilient members, and a shoulder on said stud constructed and arranged to engage said resilient members and move the extremities thereof against said abutments, whereby said resilient members will be held contracted to prevent the withdrawal of said stud from said aperture.

60 7. A fastener having, in combination, a holder provided with an aperture adapted to receive a stud, a pair of resilient members arranged within said holder transversely of said aperture, said resilient members being normally movable toward and away from

each other, a stud adapted to be inserted in said aperture between said resilient members, said stud having an annular groove formed adjacent to one end thereof, the edge of said groove farthest from said end being 70 rounded and adapted to engage and spread said resilient members, and means on said holder outside of the normal path of movement of said resilient members adapted to be engaged by said resilient members and prevent the spreading thereof. 75

8. A fastener having, in combination, a holder including a top and a back secured to said top, said top and said back having apertures substantially alining with each 80 other, a pair of resilient members arranged in said holder transversely of said apertures, a spacer formed integral with said back arranged between said resilient members and in engagement with said top, said spacer 85 being tapered to engage and spread said resilient members during the assembling of said fastener and a stud constructed and arranged to be inserted between and held by said resilient members. 90

9. A fastener having, in combination, a holder provided with an aperture, a resilient member arranged within said holder and normally movable transversely of said aperture, a stud adapted to be inserted in said 95 aperture, said stud having a shoulder constructed and arranged to be engaged by said resilient member, and means on said holder arranged outside of the normal path of movement of said resilient member adapted 100 to be engaged by said resilient member to prevent the disengagement of said resilient member from said shoulder.

10. A fastener comprising a holder consisting of two substantially parallel walls 105 separated by a space, said holder having a stud receiving aperture, a pair of resilient members arranged between the walls of said casing and transversely of said aperture, the free ends of said resilient members 110 being normally movable toward and away from each other, a stud adapted to be inserted in said aperture between said resilient members, said stud having a shoulder adapted to be engaged by said resilient members, and means on said holder outside of the normal paths of movement of said resilient members constructed and arranged to be engaged by said resilient members when the same are deflected from their normal paths 115 to prevent the movements of said members 120 away from each other.

11. A fastener comprising a holder consisting of two substantially parallel walls separated by a space, said holder having a 125 stud receiving aperture, a pair of resilient members arranged between the walls of said casing and transversely of said aperture, said resilient members being substantially the equivalent in thickness to the space be- 130

tween said walls, a stud adapted to be inserted in said aperture between said resilient members, said stud having a shoulder adapted to be engaged by said resilient members, and means on said holder outside of the normal paths of movement of said resilient members constructed and arranged to be engaged by said resilient members when the same are deflected from their normal paths

to prevent the movements of said members 10 away from each other.

In testimony whereof I have hereunto set my hand in presence of two subscribing witnesses.

GEORGE W. HOAR.
